UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

DRILLING APPARATUS.

1,252,375.

Specification of Letters Patent. Patented Jan. 1, 1918.

Application filed July 5, 1912. Serial No. 707,715.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Drilling Apparatus, of which the following description, in connection with the accompanying drawings, is a specification, like characters on the drawings representing like parts.

This invention relates to apparatus for drilling holes, being more particularly, though not exclusively, concerned with quarrying or mining tools, of that type in which the drill tool with its drill-bit is sunk bodily into the hole as it is being drilled.

My invention will be best understood by reference to the following specification, when taken in connection with the accompanying illustration of one specific embodiment thereof, while its scope will be more particularly pointed out in the appended claims.

Referring to the drawings:

Figure 1 is a central vertical longitudinal section, partly in elevation, of the specific drilling tool embodying my invention, with the outer end of the aperture fluid conduit and its swivel joint broken away, showing the drill sunk into a drilling hole in the stone or other material, the latter being shown in section;

Fig. 2 is a sectional view, partly in elevation, on an enlarged scale on line 2-2 of Fig. 1, illustrating the rotating and guiding mechanism and its driving motor;

Fig. 3 is a sectional view on an enlarged scale on line 3-3 of Fig. 1;

Fig. 4 is a sectional view on an enlarged scale on line 4-4 of Fig. 1;

Fig. 5 is a sectional view on an enlarged scale on line 5-5 of Fig. 1.

Fig. 6 is a detail sectional view on line 6-6 of Fig. 5;

Fig. 7 is a detail sectional view on line 7-7 of Fig. 5;

Fig. 8 is a detail sectional view on line 8-8 of Fig. 5;

Fig. 9 is an enlarged detail elevation, partly in vertical longitudinal section of the outer end of the pressure-fluid conduit, illustrating the swivel joints; and

Fig. 10 is a central vertical longitudinal

section of a modification of the feeding cylinder and piston.

Referring to the drawings, and to the embodiment of my invention which I have there shown for illustrative purposes, I have there disclosed a drilling apparatus having a suitable drill tool 11, which may be of the impact hammer type, provided with a drill-bit 12, which may be non-rotatably held in any suitable manner in a casing 13 of the drill tool. The drill tool may be electrically or mechanically driven, but herein is of the pressure-fluid type, and is provided with a piston hammer 14 adapted to strike one end of the drill-bit 12 in a usual and well-known manner, the piston being reciprocated under the influence of a suitable pressure-fluid, as for example, compressed air, admitted to the tool through a suitable pressure-fluid conduit 15, the latter preferably having an axial or central attachment to the upper or outer end of the tool. The detailed construction of the tool is of no consequence as bearing upon the broad principles of my invention, the construction of the tool shown, however, being similar in its general character to that shown in my prior U. S. Patent No. 853,921, dated May 4, 1907.

The pressure-fluid conduit 15 may be secured to the drill tool in any suitable manner, but I have herein shown for this purpose connecting devices which afford a means for quickly and conveniently, yet securely, attaching the conduit to the tool in such a manner that they do not become disconnected by reason of the vibration to which the parts are subjected, while at the same time permitting the apparatus to be readily dismounted at will. To this end, I have provided a tubular plug 16, constituting a conduit threaded into the outer or upper end of the drill casing 13, and held against rotation with respect to the drill tool by suitable means preventing the parts from unscrewing, herein a collar 17 suitably inter-engaging with the plug 16 and the tool casing 13. In the present instance, this collar is provided with one or more teeth 18, normally engaging suitable recesses 19 provided in the tool casing 13, and is mounted to slide on the plug 16 into and out of inter-engagement with the tool casing, but is held against rotation on said plug by one or more

keys or feathers 20, (Fig. 8) freely movable in key-ways 21 provided in the plug. Suitable means are provided for normally holding the collar 17 in inter-engagement with the tool casing 13, herein a spring 22 bearing at one end against said collar and at its other end against a shoulder 23 provided on the plug 16. By this means, the tool casing 13 is normally locked against rotation with respect to the plug 16, and is thus prevented from unscrewing from the latter, and yet may be readily unscrewed at will by simply raising the collar 17 against the tension of the spring 22 to withdraw the teeth 18 out of engagement with the recesses 19.

The plug 16 may be secured to the conduit 15 in any suitable manner, but I have herein shown these parts threaded together, the plug being provided with a reduced externally-threaded portion 24, threaded into the interior of the conduit 15. As a means for locking the conduit and plug against accidental unscrewing, I may provide the lower terminal portion of the conduit with a series of teeth 25, and the upper terminal portion of the plug with a series of teeth 26, herein in the form of ratchet teeth, one set inclined in the opposite direction from the other, and having suitable engaging means to lock them against relative rotation. This locking means may consist of a collar or sleeve 27, embracing the terminal portions of the conduit and plug, and provided with suitable means engaging the two sets of teeth, herein oppositely acting yielding spring pawls, or the like, 28 and 29, herein formed integral with the sleeve 27. These may be conveniently formed by slotting the sleeve or collar 27, as shown in Fig. 1, thus forming tongues, which may be bent inwardly as shown in Figs. 6 and 7, suitably to engage the two sets of teeth 25 and 26. Preferably the sleeve is slotted as at 30, to enable its application to and removal from the conduit and plug.

Preferably the outer terminal portion of the conduit 15 is constructed in a manner similar to the inner terminal portion just described, and is similarly secured to a nipple 31. The conduit may receive its supply of pressure-fluid from a suitable supply conduit 32, herein a usual form of flexible conduit or hose, having swiveled connection with the conduit 15, so as to permit the latter to be rotated during the operation of the tool, while allowing the conduit 32 to remain relatively fixed. This swiveled connection may be of any suitable construction, but herein there is connected to the flexible conduit 32 a tubular swivel member 33, provided with an outwardly extending lateral annular flange 34, abutting against the end of the nipple 31, and held in engagement therewith by suitable means, herein a collar 35, provided with an inwardly extending annular flange 36 encircling the swivel member 33.

Interposed between the flanges 34 and 36 is a suitable packing 37 to prevent leakage of the pressure-fluid. The collar 35 may be secured to the nipple 31 in any suitable manner, as by providing the collar with an internal screw-thread threaded onto a corresponding thread formed externally upon the nipple. By this means, the collar may be adjusted to compress the packing 37 and insure a non-leaking though freely swiveling connection between the parts. The collar may be secured in the desired position of adjustment by suitable means, herein a clamp-screw 38 passing through ears 39 provided on the collar.

The conduit 15 serves not only as a means for conducting the supply of pressure fluid to the tool, but also as a shank by means of which the tool may be manipulated and supported and rotated, while at the same time permitting the tool and shank to be fed in any suitable manner toward the work, as for example by feed means which will be described hereinafter. As a means for supporting and guiding the shank or conduit 15, and imparting a rotary movement thereto, I may provide a rotating mechanism and suitable motive-power means for operating the same, which will presently be described. Herein the rotating mechanism and its motor and the tool-feeding mechanism are mounted upon a column 40, which may be of any usual construction, having at its lower terminal portion a yoke 41, which may be provided with jack-screws 42-42 resting upon blocks 43-43 supported upon the floor of the quarry or mine. The upper portion of the column which is shown broken away may be suitably equipped to engage the roof or an over-hanging projection or a beam in the mine or quarry in a usual and well-known manner, which it will be unnecessary to show and describe herein since the character of the support *per se* is not essential to a proper understanding of my present invention. The column 40 may be provided with a saddle 44, swiveled at 45 thereon, and this saddle may support the conduit 15 by suitable means, which will presently be described.

Referring now to the means for moving the conduit 15 in opposite directions to advance and retract the drill tool, I provide suitable means, herein a feed cylinder 46 and piston 47, the former being suitably supported upon the saddle 44, as for example by a swiveled shell 48, which permits the cylinder together with the parts carried thereby to be swung laterally. The conduit 15 passes through the cylinder 46 and piston 47, the latter being provided with a tubular extension 49 passing through the rear end of the cylinder. The cylinder may be provided with a suitable packing 50, encircling the piston extension 49 to prevent leakage of the

115

120

125

130

pressure-fluid at that point. The forward end of the cylinder may be provided with a gland 51 having a suitable packing 52, encircling the conduit 15 to prevent leakage of 5 the pressure-fluid from the front end of the cylinder.

In order that the longitudinal movement of the feed-piston in its cylinder may be utilized to impart a like movement to the 10 shank 15 and the drill tool carried thereby, the piston may be secured to the conduit 15 by means permitting feeding engagement of the piston with the conduit at different points along the latter. I have provided for 15 this purpose frictional clamping means comprising an internally tapered member 53 concentric with and having screw-threaded engagement with the tubular extension 49 of the piston member and one or more frictional engaging devices, herein three seg- 20 mental members 54 interposed between the internally tapered portion of the member 53 and the periphery of the conduit 15, and preferably having an external taper corre- 25 sponding to the internal taper in the member 53. I preferably provide suitable yielding means tending to hold the frictional engaging devices 54 out of engagement with the conduit 15, herein a spring 55. The 30 member 53 may be provided with a suitable hand-wheel 56, by means of which the same may be rotated to cause the members 54 to grip the conduit 15 at any desired point along the latter. It will now be evident 35 that if the gripping devices just described be caused to grip the conduit 15 when the piston 47 is at the rear or right-hand end of the cylinder (Fig. 1), and pressure-fluid be supplied to the right-hand end of the cylin- 40 der, the piston will move forwardly or toward the left, under the influence of the pressure-fluid, and will consequently feed the conduit and the attached drill tool toward the left, and advance the same into the 45 work. When the feeding movement has continued until the piston has reached the forward end of its cylinder and the feeding movement is thereby arrested, the gripping device may be released from the conduit, and 50 the piston returned to its initial position. The gripping devices may then be utilized to take a fresh hold upon the conduit at another point in its length, and the piston advanced once more as before, and this method 55 of operation may be continued indefinitely, being limited only by the length of the conduit.

The piston 47 may be controlled by any suitable means, but I have herein shown for 60 this purpose a plug valve 57, swiveled in the cylinder 46, the latter having two ports 58 and 59 leading to opposite ends respectively of the cylinder and adapted to be placed, one in connection with the atmosphere and 65 the other with a source of fluid-pressure sup-

ply and vice versa, by said valve, the latter for this purpose being provided with a seg- 70 mental admission port 60 and an exhaust port 61, the latter communicating with an axial outlet 62. The outer end of the valve 70 75 57 may be provided with a suitable grasping handle 63, by means of which the valve may be oscillated to at one time establish communication between the port 58 and a port 64 leading to a source of pressure-fluid supply and the port 59 in communication with the atmosphere; and at another time place the port 59 in communication with the source of pressure-fluid supply and the port 58 in communication with the atmosphere. 80 Thus it will be seen that by properly ma- 85 nipulating the valve, the piston 47 may be caused to travel in either direction in its cylinder 46 under the influence of the pres- 85 sure-fluid.

Referring now to the rotating mechanism and its motor, the rotating mechanism preferably comprises a roller or other simi- 90 lar clutch comprising a series of rollers or balls 65, engaging the periphery of the con- 95 duit 15 and mounted in a suitable cage 66, encircling the conduit. The cage 66 receives the intermittent rotary motion from a ring 67 swiveled in a casing 68, herein forming a part of the cylinder casting. This ring is 95 provided with suitable inclined depressions 69 to receive the balls or rollers 65, and serv- 100 ing to wedge the latter into driving engagement with the conduit when the ring is ro- 105 tated in one direction, while permitting the rollers or balls to be freed from such driv- 110 ing engagement upon a partial rotation of the ring in the opposite direction. Thus if the ring 67 be rotated contra-clockwise, (Fig. 2) the balls or rollers 65 will be crowded into engagement with the conduit 15, so as to rotate the latter, while upon a return movement of the ring, the cage 66 with its rollers or balls 65 is rotated clock- 115 wise by suitable means, herein a spring 70 bearing at one end against a pin 71 engag- 120 ing the teeth 72 of the cage. The spring 70 is locked in a recess 73 provided in the ring 67, there being provided a suitable screw- 125 threaded plug 74 to permit the introduction and adjustment of the spring. This spring serves to urge the balls or rollers 65 con- 130 stantly toward one end of their respective recesses 69, thus preventing them from be- 135 coming wedged in the other ends of their respective recesses, as would otherwise be the case. By this means, the roller clutch mechanism just described is capable of guid- 140 ing the conduit 15 and at the same time im- 145 parting a step-by-step rotative movement thereto, while permitting the tool to be fed into the hole by the feed mechanism hereinbefore described.

The ring 67 may receive an oscillatory motion from a suitable motor, herein a pres- 130

sure-fluid motor, comprising a cylinder 75 and piston 76, the latter being suitably connected to the ring 67 to drive the same, and herein being provided for that purpose with 5 a depression 76, which receives a gear tooth 77 formed on the ring. The motor may be of any suitable type, but herein is in the form of a simple valveless motor, having a constant pressure space 78 receiving a supply 10 of pressure-fluid from any suitable source, but preferably from a passage 79 communicating with the port 59 hereinbefore described. It will now be seen that when the valve 57 is properly positioned to 15 supply pressure-fluid through the port 59 to the rear end of the cylinder 46 to advance the tool into the work, a part of the pressure-fluid will pass through the passage 79 to the constant pressure space of the motor, 20 so as to drive the latter during the feeding of the tool. When, however, the valve 57 is properly positioned to supply pressure fluid through the port 58 to the forward end of the cylinder for the purpose of retracting 25 the drill tool, the port 59 and hence the passage 79 and pressure-space 78 of the motor, will be placed in communication with the atmosphere, so that the motor will not be driven during the retraction of the tool. 30 Thus it will be seen that the valve exercises a conjoint control of the tool feeding mechanism and the tool rotating mechanism, and is capable of admitting pressure fluid to the rotating mechanism and feeding mechanism 35 to cause the tool to be advanced and rotated, or may be operated to withhold pressure-fluid from the rotating mechanism while supplying pressure-fluid to the feeding mechanism to cause the tool to be retracted. 40 Referring now more particularly to the operation of the motor itself, the fluid pressure in the space 78 acts against a reduced portion 80 on one end of the piston 76, and hence tends to constantly urge the latter toward the left (Fig. 2), while pressure exists 45 in the space 78. The opposite end of the cylinder 75 is provided with one or more ports 81, directly communicating with the atmosphere. Hence the piston 76 will be 50 moved toward the left (Fig. 2) under the influence of the pressure-fluid on a small area of its reduced portion 80, until the latter passes beyond a port 82, whereupon communication is established between said port 55 and the constant pressure-space 78, and the pressure-fluid is conducted through said port and through a passage 83 and port 84 to the left-hand end of the cylinder. Now, 60 since the area of the left-hand end of the piston 76 is greater than that of the reduced portion 80, the pressure acting against the latter will be over-balanced, and the piston will return to its initial position, whereupon the reduced portion 80 will cut off commun-

nication between the pressure supply space 65 78 and the port 82, and the pressure fluid at the left-hand end of the piston will exhaust to the atmosphere through the ports 81. There may be provided a suitable vent 85 leading from the annular space about the reduced portion 80 to the atmosphere to permit the free entrance and exit of atmospheric air at this point, and prevent the formation of a cushion. If desired, the cylinder ends may be provided with plugs 86 75 and 87 having cushioning springs 88 and 89, respectively, operating in a well-known manner to cushion the piston at each end of its stroke.

It will now be evident that if the drill tool 80 be operated to drill a hole into the side, or bottom, or the roof, of a mine, quarry, or other place, a step-by-step rotative movement may be imparted to the tool, so as to present the cutting edges of the drill-bit at 85 a fresh place with each stroke, and at the same time, the tool is fed bodily by the feeding mechanism into the drilled hole to any desired depth within the range of the conduit 15, and the latter will be properly 90 guided and held against lateral movement during its rotation. It will also be evident that the tool will continue to receive its proper supply of pressure fluid through the use of the swiveled connection, without interfering in any way with its rotation.

Referring now to Fig. 10, wherein I have shown a modification of the feed cylinder and its piston, 90 is the feed cylinder and 91 the feed piston, differing from the feed 100 piston and cylinder hereinbefore described, in that the piston 91 is provided with a forwardly extending tubular extension 92, passing through the forward end of the cylinder, the latter being provided with a suitable 105 gland 93 having a packing 94 encircling the piston extension to prevent the leakage of pressure-fluid from the cylinder at this point. One of the advantages resulting from this construction is that since the pressure-fluid conduit 95 is inclosed by the piston and its extensions where it passes through both ends of the cylinder 90, the conduit is not required to pass directly through the front cylinder head and hence is not obliged to have 110 a good sliding fit with any gland or packing, and accordingly the conduit need not be accurately mounted, but may be comparatively rough and unfinished. In this form of my invention, as in the form first described, the 115 piston is secured to the conduit by suitable gripping means, similar to that hereinbefore described, whereby the piston may feed the tool forward into the work, and then be retracted so as to take a fresh grip upon the 120 conduit, and again feed the tool forward.

My invention is not limited to the employment of any particular form of motive

power, nor is the same limited to the employment alone of an impact drill member, as distinct from a reciprocatory drill.

While I have herein shown two embodiments of my invention for illustrative purposes, and have disclosed and discussed in detail the construction and arrangement incidental to two specific embodiments thereof, it is to be understood that the invention is limited neither to its specific embodiments herein shown, nor to the mere details or relative arrangement of parts, but that extensive deviations from the illustrated forms or embodiments of the invention may be made without departing from the principles thereof.

Having thus described my invention, what I claim and desire by Letters Patent to secure is:—

1. A drilling machine having, in combination, a drilling tool, a shank secured to said drilling tool, means for rotating said shank, means for imparting a longitudinal movement to said shank, and a single manually operable means for conjointly controlling the operation of both of said means.

2. A drilling machine having, in combination, a drilling tool, a shank secured to said drilling tool, means for rotating said shank, feeding means for imparting a longitudinal movement to said shank in opposite directions, and means for supplying power to said rotating means and feeding means, including provision for alternatively withholding power from said rotating means while supplying power to said feeding means.

3. A drilling machine having, in combination, a drilling tool, a shank secured to said drilling tool, pressure fluid means for rotating said shank, pressure fluid feeding means for imparting a longitudinal movement to said shank in opposite directions, and means for admitting pressure fluid to said rotating means and feeding means to cause the tool to be advanced and rotated, including provision alternatively to withhold pressure fluid from said rotating means while supplying pressure fluid to said feeding means to cause the tool to be retracted.

4. A drilling machine having, in combination, a drilling tool, a shank secured to said drilling tool, pressure fluid means for rotating said shank, a pressure fluid feed cylinder and piston one of which is connected to said shank, and means including a valve for simultaneously admitting pressure fluid to said rotating means and one end of said cylinder, or withholding pressure fluid from said rotating means while admitting pressure fluid to the opposite end of said cylinder.

5. A drilling machine having, in combination, a drilling tool, a shank secured to said drilling tool, pressure fluid means for rotat-

ing said shank, a pressure fluid feed cylinder and piston one of which is connected to said shank, and means including a valve for simultaneously admitting pressure fluid to said rotating means and to one end of said cylinder and placing the other end in communication with the atmosphere, or withholding pressure fluid from said rotating means and admitting pressure fluid to said other end and placing the first mentioned end in communication with the atmosphere.

6. In a drilling apparatus the combination with a percussive drilling tool having a drill bit, of motive power means for rotating said drill bit, pressure actuated feeding means including a cylinder member and a piston member, and an adjustable connection between one of said members and said tool, whereby a longer feed than the length of the piston member's travel can be secured.

7. In a drilling apparatus, the combination with a hammer drill, of motive power means for rotating said hammer drill, pressure actuated feeding means including a cylinder member and a piston member, and an adjustable connection between one of said members and said tool, whereby a longer feed than the length of the piston member's travel can be secured.

8. A drilling apparatus having, in combination, a drilling tool having a drill bit, means for bodily rotating said drilling tool and its drill bit, means for imparting a longitudinal motion to said tool and its drill bit, and means for conjointly controlling the operation of both of said means.

9. A drilling apparatus having, in combination, a drilling tool, means for rotating said tool, feeding means for imparting a longitudinal movement to said tool in opposite directions, and means for supplying power to said rotating means and feeding means, or withholding power from said rotating means while supplying power to said feeding means.

10. A drilling apparatus having, in combination, a drilling tool, pressure fluid means for rotating said tool, pressure fluid feeding means for imparting a longitudinal movement to said tool in opposite directions, and means for admitting pressure fluid to said rotating means and feeding means, to cause the tool to be advanced and rotated, or withholding pressure fluid from said rotating means while supplying pressure fluid to said feeding means to cause the tool to be retracted.

11. A drilling apparatus having, in combination, a drilling tool having a drill-bit, means for bodily rotating said drilling tool and its drill-bit, a pressure fluid feed cylinder and piston, one of which is connected to said tool, and a single valve means for ad-

mitting pressure fluid to said rotating means and to either end of said cylinder at will.

12. A drilling apparatus having, in combination, a drilling tool having a drill-bit, pressure fluid means for bodily rotating said drilling tool and its drill-bit, a pressure-fluid feed cylinder member and piston member, one of which is connected to said tool, and valve means for simultaneously admitting pressure fluid to said rotating means

and one end of said cylinder, or withholding pressure fluid from said rotating means while admitting pressure fluid to the opposite end of said cylinder.

In testimony whereof, I have signed my name to this specification, in the presence of two subscribing witnesses.

GEORGE H. GILMAN.
